UNITED STATES PATENT OFFICE

109,461

DESIGN FOR SUNGLASSES

Carlton S. Sachs, Bronx, N. Y., assignor to The
Glembay Company, Inc., New York, N. Y., a cor-
poration of Delaware

Application November 2, 1937, Serial No. 72,585

Term of patent 14 years

To all whom it may concern:

Be it known that I, Carlton S. Sachs, a citizen
of the United States, residing in the Bronx, in
the county of Bronx and State of New York, have
invented a new, original, and ornamental Design
for Sunglasses, of which the following is a specifi-
cation, reference being had to the accompanying
drawing, forming part thereof.

In the drawing:

Figure 1 is a perspective view of sunglasses
showing my new design, and
Figure 2 is a top plan view thereof.

The eye members are substantially round, but
with flattened inner and side edges, and the for-
ward portions of the temple-bows are substan-
tially round with flat front edges, the said for-
ward portions tapering rearwardly to straight-
edged and relatively narrow portions which are
curved and enlarged at their ends.

I claim:

The ornamental design for sunglasses, as
shown and described.

CARLTON S. SACHS.
